United States Patent Office

Des. 224,395
Patented July 25, 1972

224,395

TELEPHONE SHELF

Bob R. Adams, 1/2 Bird-Adams Co., Inc., P.O. Box 38,
Doraville, Ga. 30340

Filed May 17, 1971, Ser. No. 144,362

Term of patent 14 years

Int. Cl. D25—99

U.S. Cl. D13—1

FIG. 1

FIG. 2

FIG. 3

FIG. 4

FIG. 5

FIG. 6

FIG. 1 is a perspective view of a telephone shelf embodying the new design and showing the left side and front of the shelf;

FIG. 2 is a rear elevational view thereof;

FIG. 3 is a top plan view thereof;

FIG. 4 is a bottom plan view thereof;

FIG. 5 is a right side elevational view thereof; and

FIG. 6 is a front elevational view of a modified form of the design.

The broken line representation is a house telephone which is shown for illustrative purposes only and forms no part of the design.

What is claimed is:

The ornamental design for a telephone shelf, substantially as shown and described.
